UNITED STATES PATENT OFFICE.

LEONARD V. DIXON, OF TORONTO, ONTARIO, CANADA, ASSIGNOR TO DUNLOP TIRE & RUBBER GOODS CO. LIMITED, OF TORONTO, ONTARIO, CANADA.

STOCK GUIDE FOR THE ROLLS OF MIXING MACHINES AND THE LIKE.

Application filed August 15, 1923. Serial No. 657,561.

To all whom it may concern:

Be it known that I, LEONARD V. DIXON, of the city of Toronto, in the county of York, Province of Ontario, Canada, have invented 5 certain new and useful Improvements in Stock Guides for the Rolls of Mixing Machines and the like, of which the following is a specification.

This invention is applicable to the rolls of 10 rubber mixing machines and the like for the purpose of retaining the stock between the working surfaces of the rolls and my object is to devise guiding means for the stock which will substantially prevent the stock 15 passing off the ends of the rolls, which will automatically adjust itself as the rolls are adjusted to and from one another, which will deflect any material which may pass to the outer ends of the rolls to a suitable receptacle; and in which parts particularly 20 subject to wear are readily renewable.

I attain my objects by means of the constructions hereinafter described and illustrated in the accompanying drawings in 25 which—

Fig. 1 is a plan view of part of a rubber mixing machine provided with my improved stock guide;

Fig. 2 an elevation of the parts shown in 30 Fig. 1, the rolls being shown in section;

Fig. 3 a front elevation of the same parts; and

Fig. 4 a cross section of the stock guide on an enlarged scale.

In the drawings I show a part of the frame 35 1 of the mixing machine. In this frame are supported the bearing boxes 2 for the rolls 3. One or both of these boxes are adjustable in the frame 1 so that the distance between the rolls may be varied.

The stock guide comprises two parts 4 and 5, which are formed of metal plates adapted to overlap at their adjacent edges with their inner surfaces in substantially the

45 same plane. In the preferred arrangement the adjacent edges are given a telescopic connection by means of a front plate 6 and back plate 7 riveted to one of the parts of the guide. The parts of the guide are recessed as shown to receive the front plate 6 so that the inner surface of the guide is 50 flush. The free edge of the front plate is

also preferably bevelled as shown in Fig. 4, so that any rubber stock which may enter the recess will be pressed outwardly if the 55 parts of the guide are forced towards one another instead of being jammed in the end of the recess. The parts 4 and 5 of the guide, it will be noted, are fitted to the contours of the rolls and extend between the same substantially to the plane in which the axes of the rolls lie.

The parts of the guide are so supported that each is maintained in a fixed relationship to the roll to which it is fitted, the preferred arrangement being to form a bracket 65 8 on the back of each part, which brackets are secured to the bearing boxes 2.

The guide is preferably so positioned that the back plate 7 may extend past the plane 70 in which the axes of the rolls lie to a position in which it is adapted to direct into a suitable receptacle 9 any rubber stock which, despite the controlling influence of the guide, may tend to pass outwardly after 75 it has passed the plane in which the axes of the rolls lie.

The outer edges of the guides are preferably formed of detachable plates 10, which are preferably inclined outwardly and are 85 fitted closely to the contours of the ends of the rolls. As the edges of the ends of the rolls may be bevelled in various ways, the guide may be adapted to any given roll by simply removing the plates 10 and replacing 90 them by other plates suitably shaped to conform to the rolls.

The ends of the parts of the guide-carrying detachable plates are preferably inclined outwardly so as to tend to direct inwardly 95 all material clinging to the surface of the rollers, which tends to pass off the ends. The lower end of the back plate 7 is also preferably inclined inwardly to direct material passing between the rolls away from 100 the sides of the frame.

The ends of the parts 4 and 5 projecting between the rollers are curved or inclined both axially and circumferentially of the rolls so as to tend to direct the material inwardly away from ends of the rolls at the point where the two rolls bite.

From the above description it will be seen that I have devised a construction which will

satisfactorily attain the objects of my invention as set out in the preamble of this specification.

What I claim is:—

5. 1. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted and the parts move relative to one another when the movable roll is adjusted. 50
10. 2. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted, a front plate and a back plate secured to the edge of one part of the guide and overlapping the other part, the back plate being extended past the plane of the axis of the roll. 55
15. 3. In a machine for rolling plastic material the combination with a pair of rolls one of which is provided with adjustable bearings whereby it may be adjusted to and from the other roll, of a stock guide formed in two overlapping parts fitted to the contours of the rolls, said parts being secured to the bearings of the rolls, so that each part maintains a fixed relationship to the roll to which it is fitted. 60
20. 4. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted, a front plate and a back plate secured to the edge of one part of the guide and overlapping the other part, the back plate being extended past the plane of the axis of the roll and inclined inwardly at its inner end. 65
25. 5. In a machine for rolling plastic material the combination with a pair of rolls one of which is provided with adjustable bearings whereby it may be adjusted to and from the other roll, of a stock guide formed in two parts fitted to the contours of the rolls, telescoped together at their adjacent edges with their inner surfaces substantially flush, each part being supported so that it maintains a fixed relationship to the roll to which it is fitted and the parts move relative to one another when the movable roll is adjusted. 70
30. 6. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted, a front plate and a back plate secured to the edge of one part of the guide and overlapping the other part, the back plate being extended past the plane of the axis of the roll and inclined inwardly at its inner end. 75
35. 7. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted, and the parts move relative to one another when the movable roll is adjusted, the inner ends of the parts of the guide being inclined both axially and circumferentially of the rolls. 80
40. 8. In a machine for rolling plastic material the combination with a pair of rolls one of which is provided with adjustable bearings whereby it may be adjusted to and from the other roll, of a stock guide formed in two parts fitted to the contours of the rolls, a front plate and a back plate secured to the edge of one part of the guide and overlapping the other part, the parts being recessed to receive the front plate, each part 85
45. 9. In a machine for rolling plastic material the combination with a pair of rolls one of which is provided with adjustable bearings whereby it may be adjusted to and from the other roll, of a stock guide formed in two overlapping parts fitted to the contours of the rolls, each part being supported so that it maintains a fixed relationship to the roll to which it is fitted, and the parts move relative to one another when the movable roll is adjusted, the inner ends of the parts of the guide being inclined both axially and circumferentially of the rolls. 90

Signed at Toronto, Canada, this 27th day of July 1923.

LEONARD V. DIXON.
